RADIANT GAS BURNER

Filed Nov. 2, 1948

UNITED STATES PATENT OFFICE

2,655,991

RADIANT GAS BURNER

Walter Kennedy, Cliffside Park, N. J.; The United National Bank of Cliffside Park, Bergen County, N. J., administrator of said Walter Kennedy, deceased, assignor to William D. Kennedy, Englewood, N. J.

Application November 2, 1948, Serial No. 57,917

11 Claims. (Cl. 158—113)

1

This invention relates to gas burners of the radiant-type adapted for use in conjunction with the various types and kinds of gas supply. More particularly, the invention deals with burners of the type and kind under consideration adapted for use in broilers or broiler compartments of ranges to provide quick and effective broiling operations upon various types and kinds of food. The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a diagrammatic side view of a portable broiler, showing one of my improved broiler units mounted in the upper portion thereof.

Fig. 2 is an enlarged sectional view on the line 2—2 of Fig. 1, showing only the broiler unit.

Fig. 3 is a perspective view of part of one of the burner tubes of the broiler, showing part of one of the radiants thereon; and

Fig. 4 is a section on the line 4—4 of Fig. 2, with parts of the construction broken away.

In Fig. 1 of the drawing, I have shown, to illustrate one adaptation and use of my invention, a diagrammatic outline of a portable broiler 10, having suitable vertical supports 11 therein for a pan or receptacle 12 to be positioned in predetermined arrangement in the chamber 13 of the broiler and with respect to the broiler unit 14, which is arranged in the upper part of the broiler and beneath a vent or flue chamber 12' at the top of said broiler. The unit 14 is shown more in detail in Fig. 2 of the drawing, the unit comprising an elongated manifold 15 of rectangular cross-sectional form to which is attached a rectangular frame 16, part of the frame being formed by the manifold 15.

Coupled centrally of the manifold 15 is a gas and air Venturi tube 17, with which a suitable supply 18 is coupled, the latter extending through one wall of the broiler 10, as diagrammatically seen in Fig. 1. The housing 15 has, spaced longitudinally of the inner wall thereof, sleeve-like members 19 extending into and out of the manifold to form seats for one end of a corresponding number of burner tubes 20.

In Fig. 2 of the drawing, four of such burner tubes are shown coupled with the manifold.

Each of the tubes 20 are of the same construction and these tubes are formed from two semi-circular members having laterally extending flanges, as at 21. The flanges are passed outwardly longitudinally at spaced intervals to form flat and relatively thin burner discharge openings 22, note Fig. 3. Between the discharges 22, the flanges are welded or otherwise secured to-

2

gether where they abut, as at 23. The flange portions 21 terminate short of the ends of the tube to provide cylindrical mounting ends which fit into the sleeves 19, as seen at 24, in Fig. 4 of the drawing. The other end fits into a cap 25 welded or otherwise secured to the member 16' of the frame 16.

The frame 16 includes, on its walls, inwardly extending flange portions 26, which are arranged in alignment with the flanges 21 on the tubes and these flanges collectively support a series of radiants 27 in the arrangements seen in Fig. 2 of the drawing. Each radiant is of the same construction and, therefore, the brief description of one will apply to the other. Each radiant comprises a U-shaped or elongated channel-shaped plate of perforated sheet metal, preferably of the heat resisting type, i. e., the radiant has a top wall 28 and depending side walls 29, the latter terminating in inwardly and upwardly turned flanges 30. The flanges 30 form grooves longitudinally of the lower ends of the walls 29 to receive the edges of a wire mesh strip 31 flexed to curved cross-sectional form in arrangement in the channel defined by the walls 28, 29 of each radiant. In assemblage, one radiant is disposed between the side burner tubes 20 and the corresponding side walls of the frame 16; whereas, two of the rods are disposed between adjacent tubes 20, again as clearly illustrated in Fig. 2 of the drawing. The openings or nozzles 22 extending into the arc-shaped chambers 32 formed by each of the radiants, thus providing a substantially continuous glow or reflected glow over the entire surface of the broiler unit. It will be understood, in this connection, that the curvature of the wire mesh radiants 31 produces this widespread reflection of the glow into the firebox or chamber 13 of the broiler.

It is also preferred that the housing 15 has centrally beneath each of the burner tubes 20 small burner jets 33 for directing a flame in the direction of each of the burner wall sides of the tube, so that, regardless of where the burner may be ignited, the flame will be spread throughout the entire burner area to insure combustion or ignition of all of the nozzles of the burner tubes.

On the burner unit 14 is an extending wall or flange 34 which is adapted to rest upon one or more cleats 35 in the portable broiler, as indicated in Fig. 1 and, by virtue of this construction, the entire burner unit 14 may be quickly detached from the broiler by simply raising the Venturi tube 17 off from the fitting 18 and then swinging the rear portion of the burner 14 downwardly and outwardly through the opening 36 of the broiler. In other words, the rear portion of the broiler unit 14 is supported on the fitting 18 and the forward portion thereof on the cleat or

cleats 35, upon which the flange 34 rests. By utilizing a radiant type of burner of the kind under consideration, a broiler or broiler compartment can be brought to a suitable broiling temperature in one minute or less time, thus materially simplifying and economizing on the preparation of broiled foods of all types and kinds. Furthermore, broiling with units of the kind under consideration maintains the desirable coloring in the broiled foods and simulates broiling over hot coals of an open-fire producing this result in greater efficiency by virtue of even distribution of radiant heating. It will be noted from a consideration of Fig. 2 of the drawing that the radiant elements 27 are held in position or against accidental displacement by retaining straps 37 secured in position by screws 38 directly above each burner tube. The straps 37 are of sufficient length to extend over upper surfaces of the elements 27 at each side of each tube.

It will also be apparent that burners of the type and kind under consideration can be economically constructed by reason of the simple structure of the burner tubes used in conjunction with the manifold and the frame in which the manifold is arranged and, further, in the simple structure of the radiants employed, which consist of the elongated channelled perforated strips having the inturned flanges supporting the raw edges of strips of wire mesh fabric. These strips are simply slid into the perforated strips and, when assembled, are firmly supported in said strips. The perforated strips provide free ventilation, while at the same time, producing an effective back for the glowing elements which comprise the wire mesh strips.

These burner units may be constructed in various sizes and, by virtue of the manner of assemblage, it is simply a question of the size of the manifold, the number of the tubes employed, the proportionate size of the burner frame and the number of radiant units employed therein. By standardizing on the structure of the radiant elements and the burner tubes, these various sized or capacity burners can be employed.

The use of my improved burner will be apparent from a consideration of my prior application Ser. No. 787,239; filed November 20, 1947, now Patent No. 2,572,870, in which a broiler is disclosed and the diagrammatic showing of the broiler at 16, in the present application, can be regarded as a showing of broilers of this general type and kind.

Having fully described my invention, what I claim as new and desire to secure by Letters Patent is:

1. In radiant burners of the class described comprising an elongated housing with a plurality of burner tubes extending from said housing in spaced parallel relationship to each other, each tube comprising a pair of elongated strips of semi-circular cross-sectional form and terminating at side edges in laterally extending flanges, said flanges being offset at longitudinally spaced intervals, means securing the flanges of said parts together, intermediate the offset portions, to form longitudinally of side edges of the burner tube discharge nozzles, radiant elements supported on said flanges and extending longitudinally between adjacent tubes, each of said elements comprising an upwardly curved wire mesh strip, and a perforated inverted U-shaped member supporting each strip, and said strips overlying and being arranged directly above all of said nozzles.

2. In radiant burners of the class described

comprising an elongated housing with a plurality of burner tubes extending from said housing in spaced parallel relationship to each other, each tube comprising a pair of elongated strips of semi-circular cross-sectional form and terminating at side edges in laterally extending flanges, said flanges being offset at longitudinally spaced intervals, means securing the flanges of said parts together, intermediate the offset portions, to form longitudinally of side edges of the burner tube discharge nozzles, radiant elements supported on said flanges and extending longitudinally between adjacent tubes, each of said elements comprising an upwardly curved wire mesh strip, a perforated inverted U-shaped member supporting each strip, said strips overlying and being arranged directly above all of said nozzles and means comprising a frame arranged in alignment with said tubes and elements for supporting the burner tubes and said radiant elements in assembled relationship.

3. In burners of the class described having a plurality of burner tubes arranged in parallel spaced relationship to each other with burner nozzles spaced longitudinally of opposed sides of each tube, radiant elements supported on said nozzles and disposed longitudinally between adjacent tubes, each element comprising a perforated elongated strip of predetermined cross-sectional form, and an elongated upwardly curved wire mesh body disposed on the surface of said strip exposed to said nozzles, and all of the mesh bodies of said elements being arranged directly over and in close proximity to the discharges of said nozzles.

4. In burners of the class described having a plurality of burner tubes arranged in parallel spaced relationship to each other with burner nozzles spaced longitudinally of opposed sides of each tube, radiant elements supported on said nozzles and disposed longitudinally between adjacent tubes, each element comprising a perforated elongated strip of predetermined cross-sectional form, an elongated upwardly curved wire mesh body disposed on the surface of said strip exposed to said nozzles, all of the mesh bodies of said elements being arranged directly over and in close proximity to the discharges of said nozzles and means at side edge portions of said strip supporting said wire mesh body and providing longitudinally sliding movement of the wire mesh body with respect to said strip.

5. In burners of the class described having a plurality of burner tubes arranged in parallel spaced relationship to each other with burner nozzles spaced longitudinally of opposed sides of each tube, radiant elements supported on said nozzles and disposed longitudinally between adjacent tubes, each element comprising a perforated elongated strip of predetermined cross-sectional form, an elongated upwardly curved wire mesh body disposed on the surface of said strip exposed to said nozzles, all of the mesh bodies of said elements being arranged directly over and in close proximity to the discharges of said nozzles, means at side edge portions of said strip supporting said wire mesh body and providing longitudinal sliding movement of the wire mesh body with respect to said strip, and said last named means comprising inwardly and upwardly extending flanges on said strip.

6. A radiant for burners of the character described, said radiant comprising two relatively sliding elongated parts, one part comprising a perforated shallow channelled strip having wide-

ly spaced narrow side walls, the channelled surface of said strip being directed downwardly, the other part comprising a wire mesh body of an upwardly curved cross-sectional contour, and said body being disposed on and extending over the area of one surface of said perforated part.

7. A radiant heating unit of the character described, said unit comprising a tubular housing into which a gaseous mixture is adapted to be supplied, a plurality of burner tubes extending from said housing in spaced parallel relationship to each other, said tubes having laterally directed and longitudinally spaced discharge nozzles, the nozzles of adjacent tubes being widely spaced, a frame arranged in the plane of and encircling said burner tubes, a plurality of radiant elements mounted in the frame and completely covering the space between the adjacent tubes, each element comprising a perforated channelled strip in the form of an inverted U-shaped member, a wire mesh strip arranged within the channelled strip and of upwardly curved cross-sectional form, means retaining the mesh strip in said channel strip, and said mesh strips overlying and being arranged directly above said nozzles.

8. A radiant heating unit of the character described, said unit comprising a tubular housing into which a gaseous mixture is adapted to be supplied, a plurality of burner tubes extending from said housing in spaced parallel relationship to each other, said tubes having laterally directed and longitudinally spaced discharge nozzles, the nozzles of adjacent tubes being widely spaced, a frame arranged in the plane of and encircling said burner tubes, a plurality of radiant elements mounted in the frame and completely covering the space between the adjacent tubes, each element comprising a perforated channelled strip in the form of an inverted U-shaped member, a wire mesh strip arranged within the channelled strip and of upwardly curved cross-sectional form, means retaining the mesh strip in said channelled strip, said mesh strips overlying and being arranged directly above said nozzles, and said last named means comprising inwardly and upwardly turned side edges on said channelled strip.

9. A radiant heating unit of the character described, said unit comprising a tubular housing into which a gaseous mixture is adapted to be supplied, a plurality of burner tubes extending from said housing in spaced parallel relationship to each other, said tubes having laterally directed and longitudinally spaced discharge nozzles, the nozzles of adjacent tubes being widely spaced, a frame arranged in the plane of and encircling said burner tubes, a plurality of radiant elements mounted in the frame and completely covering the space between the adjacent tubes, each element comprising a perforated channelled strip in the form of an inverted U-shaped member, a wire mesh strip arranged within the channelled strip and of upwardly curved cross-sectional form, means retaining the mesh strip in said channelled strip, said mesh strips overlying and being arranged directly above said nozzles, said last named means comprising inwardly and upwardly turned side edges on said channelled strip, two elements being disposed between adjacent burner tubes and extending longitudinally thereof, and one element being disposed outwardly of outermost tubes of the burner unit.

10. A radiant heating unit of the character described, said unit comprising a tubular housing

into which a gaseous mixture is adapted to be supplied, a plurality of burner tubes extending from said housing in spaced parallel relationship to each other, said tubes having laterally directed and longitudinally spaced discharge nozzles, the nozzles of adjacent tubes being widely spaced, a frame arranged in the plane of and encircling said burner tubes, a plurality of radiant elements mounted in the frame and completely covering the space between the adjacent tubes, each element comprising a perforated channelled strip in the form of an inverted U-shaped member, a wire mesh strip arranged within the channelled strip and of upwardly curved cross-sectional form, means retaining the mesh strip in said channelled strip, said mesh strips overlying and being arranged directly above said nozzles, said last named means comprising inwardly and upwardly turned side edges on said channelled strip, two elements being disposed between adjacent burner tubes and extending longitudinally thereof, one element being disposed outwardly of outermost tubes of the burner unit, said burner tubes being circular in cross-sectional form, and the nozzles thereof being disposed centrally of opposed sides of said tubes.

11. A radiant heating unit of the character described, said unit comprising a tubular housing into which a gaseous mixture is adapted to be supplied, a plurality of burner tubes extending from said housing in spaced parallel relationship to each other, said tubes having laterally directed and longitudinally spaced discharge nozzles, the nozzles of adjacent tubes being widely spaced, a frame arranged in the plane of and encircling said burner tubes, a plurality of radiant elements mounted in the frame and completely covering the space between the adjacent tubes, said element comprising a perforated channelled strip in the form of an inverted U-shaped member, a wire mesh strip arranged within the channelled strip and of upwardly curved cross-sectional form, means retaining the mesh strip in said channelled strip, said mesh strips overlying and being arranged directly above said nozzles, said last named means comprising inwardly and upwardly turned side edges on said channelled strip, two elements being disposed between adjacent burner tubes and extending longitudinally thereof, one element being disposed outwardly of outermost tubes of the burner unit, said burner tubes being circular in cross-sectional form, the nozzles thereof being disposed centrally of opposed sides of said tubes, said nozzles being formed between flange portions of the burner tubes, and said flange portions forming supports for said radiant elements.
